UNITED STATES PATENT OFFICE

GEORGE T. JOHNSON, OF COLUMBUS, OHIO, ASSIGNOR TO THE BUCKEYE STEEL CASTINGS COMPANY, OF COLUMBUS, OHIO

RAILWAY CAR

Application filed November 27, 1928. Serial No. 322,284.

This invention relates to improvements in railway cars, and especially to freight cars of the gondola type.

It has heretofore been proposed to provide such cars with hinged end doors that are pivotally connected at their lower ends to the floor of the car in such manner that they may be swung inwardly and downwardly on the floor to facilitate loading; to permit lengthy articles to project beyond the ends of the car; and, where necessary, to allow extremely lengthy articles to extend from one car into an adjacent similar car. In cars of this type, it has been the practice to provide each of the end sills with an upstanding apron against which the lower edge portion of the door abuts. Such apron being subjected to rough usage, frequently becomes battered down, and weakened, and consequently, the end door, when subjected to strong forces, has a tendency to bulge the apron outwardly, and this is a disadvantage that has been tolerated over a considerable period of time.

In such cars, the car end is constructed almost entirely of metal sheets, rolled shapes and pressings held together by rivets, and the metal corner posts rise from the car under-framing and are riveted thereto. In a closed end car, the ends are solid walls which not only tie the car sides together against bulging, but stiffen it as a whole. On the other hand, open end cars of the type with which we are dealing, must depend on the intermediate side stake or post construction, and the master stakes, called corner posts, at the ends, to resist the bulging tendency of the lading, since the end door is not tied to the car sides, except for light hand latches. The serviceability of the car therefore depends to a large extent upon the corner connections between the corner posts and the under-framing. This corner connection has heretofore been a source of weakness.

As a matter of fact, it has been customary, at the ends of open end gondola freight cars, to make the end sill, corner posts, door abutment apron, coupler striker, etc., of separate metal castings and pressings, and to connect these parts together by rivets or the like with

the result that strains placed on the parts have a tendency to shear the rivets, loosen the parts, or damage the same to such an extent that such parts become defective, and eventually practically useless for their intended purposes. 65

The primary object of the present invention is to improve the end structure of freight cars of this type, with a view of eliminating the above mentioned, and other defects which are familiar to those skilled in the art. 60

Another object is to furnish a car end consisting of an integral casting which includes the coupler striker, the end sill, the door abutment apron, the corner posts, the corner post caps, the door latch brackets, the push pole pockets or cavities, some of these portions having cored holes to facilitate applying fixtures and making connections. 70

In general, such an integral construction allows metal to be removed from where it is not useful, and placed at points where needed. It presents smooth rounded surfaces and fewer joints, reduces corrosion and accidents to a minimum, and eliminates points of stress concentration. It saves the work incident to collecting a multiplicity of parts, and it reduces the number of rivets required. Integral car ends, in accordance with my invention, will dispense with a large number of separate pieces, and effect a very substantial reduction in weight. 75 80

With the foregoing objects outlined and with other objects in view which will appear as the description proceeds, my invention consists in the novel features hereinafter described in detail, illustrated in the accompanying drawings, and more particularly pointed out in the appended claims. 85 90

Referring to the drawings,

Fig. 1 is a fragmentary top plan view of my improved car end with certain additional parts attached thereto.

Fig. 2 is a front elevation of the same. 95

Fig. 3 is an end elevation.

In general, my improved car end consists of a substantially U-shaped metal casting made up of the cross bar 1 and the corner posts 2. Each corner post is substantially 100

of angle shape in horizontal cross section, and includes vertically disposed wings 3 and 4, which merge at their upper end into an integral cap 5 that covers the opening formed by the angle, and ties the upper ends of the wings together to reinforce the same. Each cap has a lateral extension 6 that is united with the wing 4 by a triangular rib 7 that is preferably vertically disposed.

10 The integral corner post cap provides substantial advantages over the intricate details in built-up constructions, as to the number of parts and ease of riveting. Its greater thickness resists corrosion, fewer rivets are exposed, and greater stability is provided.

15 Apertures 8 in the extension 6 serve to receive rivets that are employed to connect the cap to a metal bar 9, used at the upper edge of the side of the car.

20 The wing 4 is also apertured at 9a to accommodate rivets employed in connecting the side plates of the car body to the corner posts, and each wing is also preferably provided with an apertured ear 10 through which a

25 rivet may be passed for connecting the wing 4, not only to the side plate, but also to the reinforcing bar 9. This ear is positioned in close proximity to the cap, so as to form a support for one end of the bar 9.

30 Each corner post is provided with a door latch bracket 11, which is integral with the wing 3 and consists of an upwardly extending arm 12 that is well ribbed, as shown at 13, for greater strength and permanency.

35 An enlargement 14 of each wing 4, is provided with holes 15 to receive the rivets or the like, used in connecting my improved car end casting to the underframing of the car.

40 An outwardly extending ear 16 at the lower end portion of each wing 4, forms the extremity of the cross sill 17, which is preferably of channel shape throughout the greater portion of its length, the channel being formed with vertical webs 18, a horizontal floor 19, and flanges 20 which conform to the irregular lower edges of the webs 18. Each flange 20 merges at its outer extremity into a short leg 21 that is reinforced inwardly by an angular rib 22 that is united 45 with the lower extremity of the corner post. The metal of the casting, near the outer ends of the webs 18, is shaped to provide push pole pockets 23. The provision of these pockets in this manner is an example of how

50 readily and well, such details can be taken care of in an integral structure, without adding weight.

55 It has been the practice in the past to mount the coupler striker on the draft sills of the underframing of the car, and as the striker is made of one or more pieces of metal connected to the draft sills by rivets or the like, obviously such a structure is a source of weakness. To eliminate this disadvantage, I form the coupler striker as a portion

of my integral end casting, and to this purpose, the floor 19 is extended outwardly at its medial portion, as shown at 24, and the metal of this extension merges into a frame 25, having sides 26, each of which is reinforced by a laterally extending head 27 that merges into a horizontally disposed rib 28 that connects the side with one of the webs 18.

70 The carrier bar 29 of the striker is reinforced by a horizontally extending flange 30, and a vertical rib 31, and the top bar of the frame is also strengthened by a somewhat similar flange 32, and a plurality of vertical webs 33. It is evident that the construction is such that blows imparted to the striker will 75 be transmitted equally to the webs 18, floor 19, and finally distributed over the entire casting.

75 Another improvement provided by my casting, resides in the abutment 34 for the end door. Prior to the present invention, such an abutment was usually formed by the vertical wing of an angular shaped pressed metal plate, riveted to the end sill. Owing to the rough usage to which cars of this type 80 are subjected, the edge of such apron has often been battered down and bulged outwardly, with the result that the apron, not only failed to properly perform its function, but it was liable to cause accidents. To overcome this difficulty, I make such apron an 85 integral part of my casting, and I construct the same in such a way that it will hold its original shape indefinitely, and will prevent injury to the operators, even should an operator fall upon the apron. In my structure, 90 I extend upwardly from the inner edge of the floor 19, a web 35 which merges at its lower end into the metal of the floor, and at 95 its ends, is integrated with the wings 3 of the corner posts. At this point, I desire to call attention to a great advantage of this type of construction which may be seen by comparing the detail at the lower portion of the corner posts with that of usual construction.

100 The integral construction is much more rugged and rigid, because the cross sectional areas of a few rivets are not depended upon to hold the posts upright, but a deep section X-X, (see Fig. 2), of cast construction, 105 is used instead. Moreover, an integral connection of this character is not open to the objection of working loose under repeated loading.

110 The door abutment 34 is thicker than the abutments made heretofore, and it is beaded at the wearing edge, as shown at 36, for strength and accident prevention, and it will be noted that the bead extends outwardly at 115 its central portion to a maximum degree, and is gradually tapered from this point towards its ends, as best shown in Fig. 1, and the bead, as well as the web 35, is reinforced by 120 ribs 37 and 38, that are integral with the bead, web 35 and floor 19. The rib 37 is of 125

greater length than the ribs 38, and it extends outwardly to the striker 24 to strengthen the latter.

It is apparent that the dropping of heavy articles on the bead 36 or the shifting of the load on the same, will not batter the door abutment down, as is the case with rolled metal abutments which have been used in the past. My apron being an integral part of the casting, can extend entirely across the car, and it is so braced and so proportioned that it is much stronger and more durable than the separate metal pressing heretofore employed.

15 From the foregoing, it is believed that the construction and advantages of the invention will be readily appreciated by those skilled in the art, and it is evident that changes may be made in the details presented, 20 without departing from the scope of the invention as claimed.

What I claim and desire to secure by Letters Patent is:

1. A car end formed of a substantially 25 U-shaped integral metal casting consisting of a cross bar and corner posts, said posts forming continuations of the cross bar.

2. A car end formed of a substantially U-shaped metal casting, providing a cross 30 bar and corner posts, each post being angular shaped in cross section and forming an integral continuation of said cross bar.

3. A car end formed of a substantially U-shaped metal casting, including a cross bar 35 and corner posts, each post being of substantially angular shape in horizontal section, and formed of wings, and a cap at the upper end of each post, integral with said wings.

4. A one-piece metallic car end including 40 a cross bar and corner posts, the cross bar being of substantially channel shape, and the corner posts being substantially angular in cross section to provide wings, one wing of each post merging into the channel shaped portion of the cross bar.

5. A one-piece metallic car end including a cross bar and corner posts, each post being of substantially angular shape in horizontal cross section, to provide wings, a post cap 45 integral with the wings of each post and provided with a lateral extension, and a rib uniting said extension with one of said wings.

6. A one-piece metallic car end consisting of a cross bar and corner posts integral therewith, the cross bar having a substantially vertical web, and each corner post having an inwardly extending transverse wing, said wings merging into the ends of the web.

7. A one-piece metallic car end including a cross bar and corner posts, each post having an integral latch bracket braced by a web that is integral with the bracket and the corner post on which the bracket is mounted.

8. A one-piece metallic car end including a cross bar and corner posts, the cross bar

having a vertical web positioned above the lower ends of the corner posts, each corner post having a transversely extending wing, said wings merging into the ends of the web.

9. A one-piece metallic car end, including a cross bar and corner posts, each corner post being of substantially angular shape in horizontal cross section, and having a longitudinally extending wing and a transversely extending wing, said cross bar having upper and lower webs, the ends of the upper web merging into the longitudinal wings.

10. A one-piece metallic car end including a cross bar and corner posts, each post being substantially angular in shape in horizontal section, and formed of wings, a cap integral with the upper ends of the wings and joining the latter, one of said wings having an apertured ear spaced from the cap to provide a recess to receive the flange of an edge bar.

11. A one-piece metallic car end including a cross bar and corner posts, each post having a longitudinally extending wing, the lower end portion of the wing being extended both forwardly and rearwardly, said cross bar having a channel shaped portion merging into the rear extension of the wings.

12. A one-piece metallic car end, including a cross bar and corner posts, and push pole pockets positioned at the lines of intersection between the cross bar and corner posts.

13. A one-piece metallic car end including a cross bar and corner posts, said cross bar having substantially channel shaped portions merging into the corner posts, and push pole pockets positioned in the end portions of said substantially channel shaped parts.

14. A one-piece metallic car end including a cross bar having a floor portion, a web depending from the floor portion, a flange reinforcing the lower edge portion of the web, and a push pole pocket positioned in said web.

15. A car end including a floor portion, a door abutment integral with the floor portion and rising from the latter, and a beading integral with the upper edge portion of said abutment.

16. In a car end, a metallic floor portion, an upstanding metallic web integral with the floor portion, a beading integral with the upper edge of the abutment, and ribs reinforcing the abutment and extending from the latter to said floor portion.

17. In a car end, a one-piece cross bar including a floor, an upstanding door abutment, a beading extending along the upper edge portion of the abutment, and tapering gradually from its center portion toward its ends, and reinforcing ribs integral with the floor, abutment and beading.

18. In a car end, a one-piece metallic cross bar including a floor, a coupler striker frame depending from the central portion of the rear edge of the floor, a pair of webs depend-

ing from the floor at opposite sides of the striker frame and merging into the sides of the latter, and a door abutment apron projecting upwardly from the front edge of the floor.

19. A one-piece metallic car end including a cross bar formed of a floor portion, a door abutment portion, a striker frame and webs, the webs being located at opposite sides of the striker frame and having their inner ends merging into the latter, the upper ends of the webs and frame merging into the floor, and the door abutment extending upwardly from the floor and merging into the latter, and integral ribs joining said portions for distributing strains.

20. A one-piece metallic car end, including a cross bar and corner posts, and a coupler striker arranged at the central portion of the cross bar and forming an integral part of the latter.

21. A one-piece metallic car end including a cross bar and corner posts, the cross bar comprising a floor, a coupler striker depending from the central portion of the edge of the floor, webs arranged at opposite sides of the striker, depending from the floor and merging at their inner ends into the sides of the striker, reinforcing flanges extending along the lower edges of the webs, and extensions from said flanges joining the same to the lower extremities of the corner posts.

22. A one-piece metallic car end including a cross bar and corner posts, each corner post having wings, said cross bar including a floor, a coupler striker depending from the floor, webs at opposite sides of the striker, depending from the floor, and merging into said striker, the outer ends of the web merging into the corner posts, a door abutment web forming part of the cross bar and extending from one corner post to the other, said door abutment web having its ends merging into certain wings of the corner posts.

23. In a railway car, a one piece casting comprising an end sill and spaced apart corner posts.

24. In a railway car, a one piece casting comprising an end sill and spaced apart corner posts, said end sill formed with a recess for reception of a panel, said posts each formed with a recess for reception of said panel and another recess for reception of a side panel.

25. A one-piece metal car end casting comprising a corner post and a horizontal arm, and a corner post cap arranged on said corner post.

In testimony whereof, I have signed this specification.

GEORGE T. JOHNSON.
